MACHINE FOR OPERATING ON RIBBON MATERIAL

Seraphine F. Bauwens, Chicago, Ill., assignor to
Bauwens Machine Company, Inc.

Application June 15, 1940, Serial No. 340,710

22 Claims. (Cl. 1—3)

The invention relates to machines for operating on bands of ribbon material and more particularly to an improved machine for forming accurately dimensioned loops or bows of such material and for stapling the same in permanent form.

One object of the invention is to provide a machine of the above general character which is operative to determine the finished length of the loop with a high degree of accuracy, to locate a plurality of stiffening members in proper relation to the ends of the loop, and to staple the parts together, all in a single operation, thereby materially facilitating the manufacture of such articles and substantially reducing the cost thereof.

Another object is to provide an improved loop forming and stapling machine which is readily adjustable for operating on ribbon material of different widths and for producing loops of different sizes.

Still another object is to provide an improved machine having a plurality of stapling mechanisms arranged for operating at spaced points on a loop of ribbon material together with novel means for actuating the mechanisms in a predetermined sequence such as to facilitate assembling the various parts of the article in the desired relationship.

Other objects and advantages of the invention will become apparent from the following detailed description of the preferred embodiment illustrated in the accompanying drawings in which:

Figure 1 is a perspective view of a loop forming and stapling machine embodying the features of the invention.

Fig. 2 is a perspective view of a finished article produced by the machine shown in Fig. 1.

Fig. 3 is a plan view of the shiftable forming and stapling unit of the machine.

Fig. 4 is a front view of the unit shown in Fig. 3 with a portion broken away to show details of the shifting means.

Fig. 5 is a sectional view taken along the line 5—5 of Fig. 3 showing details of the staple clinching die mechanism and its relation to the other elements of the machine.

Figs. 6, 7 and 8 are partially diagrammatic views showing the positions of various machine elements in successive stages of an operating cycle of the machine. Fig. 6 shows one end of the ribbon loop clamped in place at the beginning of an operating cycle, Fig. 7 shows the position of the various elements at an intermediate point in the cycle with the looped ribbon material pulled

out to the required length, and Fig. 8 shows the stapling heads in position to drive the staples through the material.

For purposes of illustration, the invention has been shown and described herein as embodied in a machine (Fig. 1) particularly adapted to form a loop like that of Fig. 2 in a band of ribbon material. Ribbon material looped in this manner is used extensively for hat bands and similar articles, the loop portion simulating a decorative bow when fitted with a cross bar of similar ribbon material. It will be understood, of course, that the invention in certain of its aspects is applicable to a variety of other uses. Accordingly, while a particular embodiment has been shown and described in detail, there is no intention to thereby limit the invention to such embodiment but to cover all modifications, adaptations and alternative constructions falling within the spirit and scope of the appended claims.

The ribbon material in the form best suited for hat bands is provided with a loop of the general type shown in Fig. 2. More particularly, in order to provide a decorative bow, the band or strip of ribbon material 10 has one end folded back upon itself to form a closed loop consisting of inner and outer layers 10a and 10b. The extreme end 10c of the strip is turned in so that the raw end is hidden between the inner and outer layers of the loop. Stiffening members 11 and 12 of fiber or other suitable material inserted in the ends of the loop serve to hold it against sagging and additionally facilitate the stapling of the ribbon material in the desired loop configuration.

As herein shown, the stiffening member 11 is secured to the inner layer 10a by a staple 13 at what will eventually constitute the outer end of the bow. The other stiffening member 12 is secured to the inner layer and the end 10c of the strip at the opposite or inner end of the bow by a similar staple 14. In each instance the staples extend only through the inner layer or layers of the material and through the stiffening member so that the clinched staple legs are hidden from view by the outer layer 10b when the bow is viewed from the front.

The machine illustrated in Fig. 1 is particularly suitable for forming and stapling loops such as that above described. In general it comprises an elongated flat base 20 upon which are mounted a pair of laterally spaced relatively movable loop forming and stapling units S1 and S2. Each of these units has a projecting portion extending outwardly from the base to permit

the strip of ribbon material 10 to be wound thereabout in loop formation. Suitable means is provided on the units for positioning the stiffening members 11 and 12 in proper relation to the ribbon material and each unit is equipped with individual stapling mechanism of conventional type for securing the parts together by means of the staples 13 and 14. A common actuator for the stapling mechanisms is carried on an upright standard 21 rising from the base 20 substantially midway between the units S1 and S2. The standard 21 also supports a shiftable gauge pin 22 which, in cooperation with the shiftable unit determines the finished length of the loop. Suitable actuating means, including, in this instance, a pivoted foot pedal P is provided for operating the various elements of the machine so as to effect the various steps of the operation in predetermined sequence.

Proceeding now to a more detailed description of the elements of the machine, the forming and stapling units S1 and S2 are of generally similar construction although differently mounted on the machine base. In the particular machine illustrated, the unit S1 is stationarily supported on the base 20 while the unit S2 is supported for movement toward and from the first mentioned unit. Movement of the latter unit is utilized to pull the looped ribbon material taut and to draw it, with the assistance of the gauge pin 22 into a loop of predetermined length as will appear presently.

In its preferred form, the stationary unit S1 comprises an elongated generally U-shaped supporting member 23 adapted to be mounted on the base 20 with its legs 25 and 26 projecting forwardly therefrom. The unit S2 likewise includes a generally U-shaped support 27 adapted to be mounted on the base 20 adjacent the first unit with its legs 28 and 29 projecting forwardly therefrom substantially parallel to the legs of the first support.

The adjoining inner legs 25 and 28 (Figs. 1 and 6-8) of the respective supports constitute the projecting portions of the units about which the ribbon material is wound and each is provided with a die mechanism for clinching the staple driven through the material by the staple driving mechanism to be described hereinafter. As the die mechanisms for the units are identical, a description of one will suffice. Briefly, the mechanism comprises a generally rectangular carrier 30 (Figs. 1 and 3-5) pivotally supported at one edge on the support leg by a rib 31 engaging in a complementary groove formed in the upper surface of the leg. At one side of the groove the leg is recessed as at 32 to provide clearance for the free end of the carrier. As shown in Figs. 4 and 5 the carrier is yieldably urged to its upper or inactive position by one or more compression springs 33, upward movement being limited by a headed stop screw 34 fixed to the leg and projecting through a registering aperture in the carrier.

To receive the legs of a staple driven through the material and the stiffening strip resting on the die mechanism, the forward end of the carrier 30 is notched as at 35 (Figs. 3 and 5) to provide a pocket for a pair of pivoted clinching dogs 36. A plate 37 screwed or otherwise secured to the end of the carrier closes the front of the pocket leaving the upper and lower ends open.

The staple clinching dogs 36 are loosely pivoted by pins 38 at opposite ends of the pocket with their inner or free ends resting on a wear

plate 39 fixed in the leg of the supporting member. The upper surfaces of the dogs are substantially flat, being inclined outwardly toward each other when in their normal position as shown in Fig. 5. Consequently, as the staple legs emerge from the under side of the stiffening member on the die mechanism and enter the pocket, they engage the inclined surfaces of the dogs which deflect them inwardly during the final portion of their advance through the material and the stiffening member. When the staples are completely driven, the carrier is forced downwardly against the action of the springs 33 so that the dogs swing about their pivots to clinch the staple legs flat against the under side of the member.

Correct relationship of the ribbon material and the stiffening members is insured and these parts are accurately centered for insertion of the staples by a gauge plate 40 provided in each unit. To enable the machine to operate on strips of different widths, the gauge plate is adjustably secured to the carrier 30 as by headed screws 41 operating in slots in the plate and threading into the carrier. The arrangement is such that the gauge plate may be shifted forwardly and backwardly in a direction crosswise of the ribbon material being operated on.

The gauge plate 40 in its preferred form as shown in Figs. 3 and 5, comprises a flat, generally rectangular metal strip having its forward edge portion cut away to define two shoulders 42 and 43 constituting adjacent sides of a generally rectangular pocket dimensioned to receive one of the stiffening members 11 or 12. The front end of the pocket and the top are left open to facilitate insertion of the stiffening members and the third side is closed by a pair of lugs 44 projecting upwardly from the front plate 37 of the carrier. The gauge plate is so positioned that the pocket formed thereby is accurately centered over the staple clinching dogs 36.

The position of the ribbon material relative to the stiffening member is controlled by an upstanding shoulder 45 located rearwardly of the pocket defining shoulder 43 and formed by recessing the face of the gauge plate as indicated at 46. To avoid sharp bends in the ribbon material, the main portion of the plate adjacent the side 42 of the pocket is beveled as at 47 (Fig. 3). An aperture 48 in the plate provides access to the stop screw 34 for adjusting the position of this screw.

With the above arrangement, the machine may be readily adjusted for operating on strips of ribbon material of different widths by simply shifting the gauge plate 40 toward or from the front of the machine. In this way the stiffening member is accurately centered over the staple clinching dogs. As the shoulder 45 determines the position of the rear edge of the ribbon material, proper location of the material relative to the stiffening member is automatically effected regardless of the width of the material.

Cooperating with each of the staple clinching die mechanisms above described, is a staple driving mechanism 50 which may be of any suitable and well known construction. The conventional mechanism shown in Figs. 1 and 8 by way of illustration, comprises a hollow arm 51 pivoted at one end between upstanding flanges 52 of a channel shaped bracket 53 and having at the other end a head 54 in which is mounted a staple driving plunger 55. The plunger is normally held in an elevated position by a coil spring 56,

A coiled compression spring 51 interposed between the bottom of the bracket and the arm 51 yieldably urges the arm and stapling head to the inactive position shown in Fig. 1. In the particular arrangement illustrated, the arm 51 constitutes a magazine for staples which are fed in well known manner into operative relation to the plunger by means of a follower 58 actuated by a spring 59. The plunger, when depressed, acts to force the staples through the material resting on the carrier 30.

To enable the stapling heads to register accurately with their associated clinching dies, the brackets 53 are rigidly secured to the outer ends of the legs 26 and 29 of the respective unit supporting members. The positioning of the brackets is such that the heads 54 on movement from the inactive position shown in Fig. 1 describe an arc intersecting the forward edge of the associated clinching die so that the head meets the same as shown in Fig. 8 whereby the staple driving plunger is aligned with the staple receiving pocket 35 and the clinching dogs 36 mounted therein.

Before the stapling mechanisms are operated to insert the staples, the ribbon material looped about the projecting staple clinching dies and the gauge pin must be pulled out to the desired length. In the machine illustrated, this is effected jointly by the shifting of one unit away from the other unit and the simultaneous shifting of the gauge pin 22 transversely of the plane of the units. As herein shown, the unit S1 is stationary, being adjustably secured to the base 20 in any suitable manner as by machine screws 61 projecting through elongated slots 62 in the supporting member 26 and threading into a ledge 63 machined along the front edge of the base 20. The provision of the slots 62 permits a substantial range of adjustment of the initial spacing of the stapling units to adapt the machine for forming loops of different length.

The shiftable unit S2 is supported and guided for sliding movement toward and from the unit S1 by a guideway formed by the ledge 63 and a cooperating bracket 64 secured to the base 20 at the rear of the unit. As best shown in Fig. 5, the bracket is formed with a forwardly projecting flange arranged to overlie the supporting member 27 of the unit, which flange terminates in a depending tongue 65 engaging in a longitudinally extending groove 66 in the face of the member.

Suitable means is provided for yieldably urging the shiftable unit toward the stationary unit to facilitate the looping of the ribbon material over the projecting portions of the units at the beginning of the operation. This means as herein shown, comprises a coiled tension spring 67 connecting between an arm 68 (Figs. 1 and 3) anchored to the stationary bracket 64 and an upstanding pin 69 fixed to the supporting member. Movement of the member under the influence of the spring 67 is limited by a stop lug 10 projecting rearwardly of the member for engagement with the end of the bracket 64.

The lug 10 additionally acts in limiting the movement of the supporting member in the opposite direction, that is, toward the advanced position. For this purpose, the lug is apertured 70 to slidably receive a threaded rod 71 anchored in the end of the bracket 64 and extending parallel to the path of movement of the supporting member. A stop nut 72 and a cooperating lock nut 73 are threaded on the projecting end 75

of the rod for engagement by the lug. Thus, by simply varying the position of these nuts, the limit position of the unit S2 can be accurately determined for loops of any desired length.

5 Any suitable means may be utilized for shifting the unit S2 from its normal rest position to the advanced position above described. The shifting means, as shown in Fig. 4, comprises a bell crank lever 75 pivoted at 76 in a slot formed in the base 20. One arm 78 of the lever projects upwardly to engage in a suitable notch or slot 79 in the supporting member 27. The other arm of the lever projects substantially horizontally along the under side of the base and is operatively connected by a link 81 with the actuating mechanism to be described hereinafter.

10 While movement of the shiftable unit S2 or of the gauge pin 22 may be utilized alone to pull out the looped ribbon material to the desired length, it is preferred to effect this operation by the joint action of the unit and the simultaneous shifting of the gauge pin in a path substantially perpendicular to the path of movement of the unit. To this end the gauge pin is mounted 15 on a generally rectangular carrier 82 slidably supported in a vertical guideway formed by a recess 83 in a bracket 84 integral with or rigidly secured to the face of the standard 21. A removable plate 85 extends over the channel to retain the carrier in the guideway, the plate being 20 notched as at 86 to provide clearance for the gauge pin in the movement of the carrier.

25 For shifting the carrier 82 and gauge pin 22 from the normal rest position shown in Figs. 1 and 6 to the elevated position shown in Figs. 7 and 8, a lever 87 is pivoted on the standard 21 at the rear of the bracket 84 with one end projecting through a slot in the bracket and engaging in a notch in the carrier. The other end of the lever is pierced with a plurality of holes 30 88 adapted to receive the hooked upper end of a link 89, the other end of which is hooked into a slot 90 in the foot pedal P. The range of movement of the carrier and gauge pin can thus be regulated by shifting the link from one of the holes 88 to another. A spring 91 acting on the outer end of the lever 87 serves to yieldably urge the carrier 82 to its lower position in which the gauge pin 22 is disposed between the clinching dies as shown in Fig. 6. Due to the provision 35 of the notch in the foot pedal, movement of the gauge pin is delayed until the pedal has been depressed a predetermined amount to effect certain other operations as will appear presently.

40 The foot pedal P, in addition to shifting the gauge pin as above described, is also utilized in this instance for swinging both stapling heads to operated or clamping position and for shifting the movable stapling unit S2 to its advanced position. The pedal thus constitutes a part of 45 a common actuating means for these elements of the machine, which actuating means also includes instrumentalities for insuring operation of the elements in the desired sequence. It will be understood, of course, that separate foot pedals 50 may be provided for operating the various machine elements or suitable power actuated means may be employed for this purpose if desired.

55 The sequence of operations followed by the exemplary machine, will be readily perceived by reference to Figs. 6 to 8 of the drawings. As the first step in the operation, the stiffening members 11 and 12 are placed in the pockets formed by the 60 gauge plates 40 of the clinching dies as previously

described and the ribbon material is wound about the dies and the gauge pin 22 with the ends overlapping at the clinching die for the unit S2 as shown in Fig. 6. The operator will normally exert a slight pull on the extended end of the ribbon material while slowly depressing the foot pedal P so as to prevent undesired slippage of the ribbon material. In the initial movement of the foot pedal, the stapling head of the unit S1 is rocked from its inactive position shown in Fig. 1 to the clamping position shown in Fig. 6 in which it acts to clamp the ribbon material 10 and the stiffening member 11 fast to the carrier 30 of the associated clinching die. In this way the outer end of the loop is definitely fixed and the parts securely held in proper relationship for the insertion of the staple. Upon further depression of the foot pedal, the unit S2 is shifted away from the unit S1 or to the left as viewed in Figs. 6 and 7 and the gauge pin 22 is simultaneously moved upwardly. This movement continues until the parts assume substantially the position shown in Fig. 7 of the drawings in which the looped material is pulled out to the desired length. It will be noted that the gauge pin 22 is raised substantially above the plane of the clinching dies so as to pull out a substantial amount of ribbon material or to increase the length of the ribbon between the respective clinching dies. This is to compensate for the difference in length of the ribbon material passing around under the side of the clinching dies. The spreading of the die units takes up the slack in the outer layer 10b of the ribbon loop and draws in the free end 10c of the ribbon until the layer 10b is of the desired length as shown in Figs. 7 and 8.

The final movement of the foot pedal serves to rock the stapling head of the unit S2 into clamping relation to the material as shown in Fig. 8 whereby to hold the parts in proper relationship until the staples are inserted. With both staple heads in the clamping position, the staple driving plungers 55 may be operated by a suitable actuating means.

In the particular machine illustrated, the means for transmitting the movements of the foot pedal P to the stapling head of the unit S1 comprises a flexible traction member including an interconnected chain 92 (Fig. 1) and a coiled tension spring 93. The chain is connected at its lower end to a cross pin 94 rigidly anchored in the foot pedal while the spring is connected to the arm 51 which carries the stapler head. Due to the provision of this spring, the blocking of the stapler head by the clinching die does not interfere with the further depression of the pedal.

The shifting of the unit S2 and rocking of the stapler head of this unit is effected in this instance by a flexible traction member in the form of a chain 95 anchored at one end to the pin 94 and at the other end to a yoke 96 which is loosely connected between the lower end of the link 81 for the unit shifting lever 75 and a similar link 97 connected to the arm 51 which carries the stapler head. Sufficient slack is left in the chain 95 so that no movement is imparted to the yoke 96 until the foot pedal has been depressed sufficiently to shift the stapler head of the unit S1 in the clamping position (Figs. 6 and 7). Thereafter the yoke follows the movements of the pedal. In the preferred form of the machine, the springs 67 and 57 are so adjusted that the yoke first shifts the unit S2 outwardly toward the advanced position defined by the stop nut 72. In this operation the yoke pivots on the link 97.

When further movement of the unit is prevented by the stop nut, the other end of the yoke is depressed and through the link 97 rocks the stapler head of the unit S2 to clamping position.

With both units in the clamping position shown in Fig. 8, the stapling mechanism may be operated to drive the staples through the ribbon material and the stiffening members 11 and 12 positioned on the respective clinching dies. This is effected in the present instance by means of a common actuator including a horizontal bar 98 (Figs. 1 and 8) pivoted as at 99 on a slide 100. The bar is of sufficient length to extend over the respective stapling heads and operative to engage and depress the staple plungers 55 when the slide 100 is moved downward from the position shown in the drawings.

As shown in Fig. 1, the slide 100 is received in a vertical guideway formed by a channel shaped groove 101 in the overhanging portion of the upright 21, which groove is covered by a notched cover plate 102. A spring 103 (Fig. 8) normally tends to hold the actuator in an elevated or inactive position.

Any suitable means may be utilized for shifting the actuator slide from its inactive position to its operated position in which the staple driving plungers 55 are depressed to drive the staples 13 and 14 in the usual way. In the particular machine illustrated, the means provided for this purpose comprises a hand lever 104 pivoted at one end on an extension 105 of the upright 21 and having at its other end a handle or manual gripping member 106. A toggle link 107 operatively connects the hand lever with the slide 100. As herein shown, one end of the link is attached to the lever by a pivot pin 108, while the other end of the link is apertured to receive a pin 109 projecting from the slide 100. The arrangement is such that when the handle 106 is pulled forwardly, the slide and actuator are shifted downwardly whereby the latter acts to depress the staple driving plungers 55 for driving staples through the material clamped between the stapler heads and their respective clinching dies. Upon release of the hand lever 104 and foot pedal P, the parts are returned to their normal positions by the various springs hereinbefore described. The looped ribbon material may then be withdrawn from the machine in the finished form illustrated in Fig. 2.

It will be apparent from the foregoing that the invention provides a novel machine for forming loops or bows in ribbon material with stiffening members accurately located at opposite ends thereof and for stapling the same together in permanent relationship. Due to the novel combination and arrangement of the parts, the work of the operator is reduced to a minimum. Likewise a minimum of skill on the part of the operator is required since means is provided for automatically insuring operation of the various machine elements in the proper sequence. Moreover, the parts are always held in their proper relationship and the looped material is uniformly pulled out to the desired length with a high degree of accuracy. The machine is simple and of sturdy construction and readily adjustable for operating on ribbon materials of different widths as well as for forming loops of different lengths.

I claim as my invention:

1. A machine of the class described comprising, in combination, a stationary member, a member shiftable away from said stationary member to determine the over-all length of a loop of ribbon

material wound about the members in loop formation, a stapling mechanism located adjacent the stationary member, a second stapling mechanism associated with the shiftable member and movable therewith, and means for operating said mechanisms simultaneously to insert staples in the ribbon material at the ends of the loop defined by the respective members.

2. A machine of the class described comprising, in combination, a stationary member, a second member supported for movement toward and away from the stationary member, said members being formed to permit a strip of ribbon material to be wound about them in loop formation, means yieldably urging the movable member toward the stationary member for positioning the members to accommodate a loop of minimum length, means for clamping the ribbon material to said stationary member to define one end of the loop, means for shifting the movable member to pull out the ribbon material wound thereover to determine the over-all length of the loop, and common means for operating said clamping means and said shifting means in predetermined sequence.

3. In a machine of the class described, in combination, a pair of members arranged in side-by-side relation in a common plane, a shiftable member supported intermediate said pair of members for movement transversely of the plane of the pair of members, said members being positioned to permit a strip of ribbon material to be wound thereabout in loop formation, means normally urging the shiftable member toward the plane of the pair of members to accommodate a loop of minimum length, means for moving the shiftable member from its normal position to pull out the ribbon material wound thereover and thereby determine the over-all length of the loop, and means for securing the overlapping portions of the ribbon material together.

4. In a machine of the class described, in combination, a pair of staple clinching dies mounted in spaced relation, a gauge pin mounted intermediate said dies for movement transversely of the plane of the dies, said dies and said pin being formed to receive a strip of ribbon material wound thereabout in loop formation, means yieldably holding said pin substantially in the plane of said dies to accommodate a loop of minimum length, means for shifting said gauge pin away from the plane of the dies to pull out the ribbon material wound thereover into a loop of predetermined length, and staple driving means cooperating with said dies for inserting staples in the ribbon material at opposite ends of the loop.

5. A machine of the class described comprising, in combination, a stationary member, a second member supported for movement toward and away from the stationary member, said members being formed to permit a strip of ribbon material to be wound about them in loop formation, means yieldably urging the movable member toward the stationary member for positioning the members to accommodate a loop of minimum length, means for clamping the ribbon material to said stationary member to define one end of the loop, means for shifting the movable member to pull out the ribbon material wound thereover to determine the over-all length of the loop, means for clamping the ribbon material to the movable member to maintain the loop at the length determined by the movement of that member, and means for securing the overlapping portions of the ribbon material together substan-

tially at the point at which it is clamped to the movable member.

6. A machine of the class described comprising, in combination, a stationary member, a second member supported for movement toward and away from the stationary member, said members being formed to permit a strip of ribbon material to be wound about them in loop formation, means yieldably urging the movable member toward the stationary member for positioning the members to accommodate a loop of minimum length, means for clamping the ribbon material to said stationary member to define one end of the loop, means for shifting the movable member to pull out the ribbon material wound thereover to determine the over-all length of the loop, means for clamping the ribbon material to the movable member to maintain the loop at the length determined by the movement of that member, and means for inserting staples through the ribbon material substantially at the points at which it is clamped to the stationary and movable members.

7. A machine of the class described comprising, in combination, a stationary member, a second member supported for movement toward and away from the stationary member, means normally urging the movable member into closely spaced relation to the stationary member, projecting portions on each member formed to receive a strip of ribbon material wound thereabout in loop formation, a lever arm pivoted at one end on the stationary member and engageable at its other end with the projecting portion of that member, a second lever arm pivoted at one end on the movable member and engageable at its other end with the projecting portion of that member, and common actuating means operable initially to rock the first lever arm into position to clamp the ribbon material to the projecting portion of the stationary member, then to shift the movable member away from the stationary member to pull out the ribbon material looped over the projecting portion of the member and thereby determine the over-all length of the loop, and finally to rock the second lever arm into position to clamp the ribbon material to the projecting portion of the movable member.

8. A machine of the class described comprising, in combination, a stationary member, a second member supported for movement toward and away from the stationary member, means normally urging the movable member into closely spaced relation to the stationary member, projecting portions on each member formed to receive a strip of ribbon material wound thereabout in loop formation, a lever arm pivoted at one end on the stationary member and engageable at its other end with the projecting portion of that member, a second lever arm pivoted at one end on the movable member and engageable at its other end with the projecting portion of that member, means for shifting the movable member away from said stationary member to pull out the ribbon material wound over the projecting portions of the member, a depressible foot pedal, and means connecting said pedal with said lever arms and shiftable means operable in the depression of the pedal to actuate the lever arms and the shifting means in predetermined sequence.

9. A machine of the class described comprising, in combination, a stationary member, a second member supported for movement toward and away from the stationary member, means normally holding the second member closely adjacent the stationary member, means operable to shift the

second member away from said stationary member, projections on each member formed to receive a strip of ribbon material wound about the same in loop formation, said ribbon material being pulled out to a loop of predetermined length by the shifting of the movable member, means on the projecting portion of each member for holding a fiber strip in fixed relation to the ribbon material, and means associated with each member for stapling the ribbon material to the fiber strip held thereby.

10. A machine of the class described comprising, in combination, a pair of supports one mounted for movement toward and away from the other, a projection on each support positioned to accommodate a strip of ribbon material wound thereabout in loop formation, a shiftable gauge pin normally positioned between said supports to project through the loop of ribbon material, means tending to hold the supports in closely adjacent relation, means for shifting the movable support away from the other support and for simultaneously shifting said gauge pin away from its normal position to pull out the loop of ribbon material to a predetermined length, stapling mechanism on each support including an arm pivoted at one end on the associated support and carrying at its other end a stapling head engageable with the ribbon material looped over the projection of that support, and means for actuating said stapling mechanisms to insert staples in the ribbon material at each end of the loop.

11. A machine for forming loops of ribbon material with transverse stiffening strips at each end of the loop, said machine comprising, in combination, a plurality of members one or more of which is shiftable away from the others to determine the length of a loop formed in a length of ribbon material wound thereabout, guide means mounted on two of said members for holding a 40 stiffening strip in predetermined relation to the ribbon material, and means associated with said two members for stapling the ribbon material and the stiffening strips together.

12. A machine for forming loops of ribbon material with transverse stiffening strips at each end of the loop, said machine comprising, in combination, a plurality of members at least one of which is shiftable away from the others to determine the length of a loop formed in a length of ribbon material wound thereabout, guide means mounted on two of said members having an extension engageable with one edge of the ribbon material and a cut-out portion for holding a stiffening strip in predetermined relation to the ribbon material, stapling means associated with each of said two members operable to staple the ribbon material and stiffening strips together, said guide means being adjustable relative to said stapling means to present ribbon materials of different width and correspondingly dimensioned stiffening strips in proper relationship to the stapling means.

13. A machine for forming loops of ribbon material with transverse stiffening members at each end of the loop, said machine comprising, in combination, a pair of supports one shiftable laterally away from the other to determine the length of a loop formed in a ribbon wound around both supports, guide means mounted on each support having a cut-out portion adapted to receive a stiffening member and defining a shoulder engageable with one edge of the ribbon material whereby to locate the stiffening member in predetermined relation to the ribbon material, a 70

stapling mechanism mounted on each support operable to staple the ribbon material and stiffening member together, and means securing the guide means to the associated support for adjustment 5 transversely of the ribbon material whereby to present materials of different widths in proper relation to the stapling mechanism.

14. A machine for forming loops of ribbon material with transverse stiffening members at each 10 end of the loop, a stationary support, a movable support, a shiftable gauge pin mounted intermediate said supports, projections on the supports positioned for the reception of a strip of ribbon material wound thereabout and over said 15 pin in loop formation, guide means on each projection for holding a stiffening member in predetermined relation to the edges of the ribbon material, means for shifting the movable support away from the stationary support and for simultaneously shifting the gauge pin away from both supports to determine the length of the loop of ribbon material, and stapling mechanism carried by each support for stapling the ribbon material and the stiffening member together.

20 15. A machine for forming loops in strips of ribbon material with stiffening members located adjacent opposite ends of the loop, a pair of supports one movable laterally toward and from the other, means urging said one support toward the other while a strip of ribbon material is wound around both supports in loop formation, means on each support for holding a stiffening member in predetermined relation to one edge of the ribbon material, means for moving said one support away from the other support, and a gauge pin mounted intermediate said supports adapted to project within the loop of ribbon material, said gauge pin being shiftable relative to the supports and operating jointly with said one support to vary the length of ribbon material between the stiffening members.

25 16. In a machine for stapling ribbon material, the combination with means for driving the legs of a U-shaped staple through a portion of material 30 presented thereto, of a die unit positioned to support the material in operative relation to the staple driving means, a guide member including a flat plate having a recess adapted to hold a stiffening member for stapling to the ribbon material, said recess defining a shoulder engageable with one edge of the ribbon material, and means securing said plate to the die unit for adjustment relative to the stapling means to accommodate ribbon material of different widths.

35 17. In a machine for stapling ribbon material, in combination, a pair of laterally spaced die units for supporting the material to be stapled, a pivoted stapling head associated with each die unit 40 adapted to be swung from an inactive position to an active position in which the head is in engagement with the material supported on the respective units, a staple driving plunger supported in each head, and mechanism for actuating said heads simultaneously including a slide reciprocal 45 toward and from the die units, and a cross member secured to said slide and engageable with the plungers of both die heads when the latter are swung into their active positions.

50 18. In a machine for stapling ribbon material, in combination, a pair of laterally spaced die units for supporting the material to be stapled, a pivoted stapling head associated with each unit, means yieldably holding said heads in inactive position, means operable to swing the heads to active position to clamp the ribbon material

against their associated die units, a staple driving plunger for each head, means for actuating said plunger to drive staples through the material, said die units acting to clinch the staples, said actuating means including a cross member engageable with both plungers, a slide pivotally supporting said cross member, a hand lever, and a toggle mechanism connecting said hand lever with said slide.

19. In a machine for forming loops of ribbon material, in combination, a base, a pair of members supported on said base, one of said members being stationary and the other movable toward and from the stationary member, projections on each member about which a strip of ribbon material may be wound in loop formation, spring means normally holding the movable member closely adjacent the stationary member while the ribbon material is being wound about the projections thereon, means for shifting the movable member away from the stationary member to pull out the ribbon material into a loop of predetermined length, adjustable stop means for limiting the travel of said movable member to accurately determine the finished length of the loop, and means for adjusting the position of the stationary member to provide for forming loops of different length.

20. In a machine of the class described, the combination of a group of at least three members each having a surface normally disposed substantially in a common plane to receive a strip of ribbon material wound thereabout in loop forma-

tion, means for holding a portion of the looped ribbon material stationary, and means for shifting the intermediate member of the group transversely of said plane to pull out one side of the looped ribbon material to a predetermined length.

5 21. In a machine of the class described, the combination of a group of at least three members each having a surface normally disposed substantially in a common plane and having a length of 10 ribbon material passing thereover, means for clamping the ribbon material to one of the outside members of the group, and means for shifting the intermediate member of the group transversely of said plane to increase the length of 15 ribbon material between the outside members of the group.

22. In a machine of the class described, the combination of a group of at least three members each having a surface normally disposed substantially in a common plane and having a length of 20 ribbon material passing thereover, means on the outside members of the group for supporting a stiffening strip adjacent the ribbon material, means for temporarily clamping the ribbon material and one of the strips to the member on which the strip is supported, means for shifting the intermediate member of the group transversely of said plane to draw out a predetermined length of ribbon material between the stiffening strips, and means for securing the stiffening strips to the ribbon material.
